US0D1017766S

(12) **United States Design Patent** (10) **Patent No.:** **US D1,017,766 S**
(45) **Date of Patent:** **** Mar. 12, 2024**

(54) **NOZZLE**

(71) Applicant: **Melnor, Inc.**, Winchester, VA (US)

(72) Inventors: **Sean Svendsen**, Columbus, OH (US);
Donald Collins Meves, Columbus, OH (US);
Eric James Fickas, Plain City, OH (US)

(73) Assignee: **Melnor, Inc.**, Winchester, VA (US)

(**) Term: **15 Years**

(21) Appl. No.: **29/834,363**

(22) Filed: **Apr. 11, 2022**

Related U.S. Application Data

(62) Division of application No. 29/786,518, filed on Jun. 1, 2021, now Pat. No. Des. 952,796, which is a division of application No. 29/718,881, filed on Dec. 30, 2019, now Pat. No. Des. 923,746, which is a division of application No. 29/670,344, filed on Nov. 15, 2018, now Pat. No. Des. 875,211, which is a division of application No. 29/598,179, filed on Mar. 23, 2017, now Pat. No. Des. 838,341.

(57) **CLAIM**

The ornamental design for a nozzle, as shown and described.

DESCRIPTION

FIG. 1 is a rear perspective view of a nozzle;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of portions of the nozzle is for the purpose of illustrating environmental structure and forms no part of the claimed design.

1 Claim, 5 Drawing Sheets
